[57] CLAIM

The ornamental design for a combined grinder and drink mixer for a pitcher, as shown and described.

DESCRIPTION

FIG. 1 is a top, front, and right side perspective view of a combined grinder and drink mixer for a pitcher showing my new design; the broken line showing of a pitcher is illustrative of environmental structure only and forms no part of the claimed design;

FIG. 2 is a top plan view thereof;

FIG. 3 is a right side elevational view thereof;

FIG. 4 is a front elevational view thereof;

FIG. 5 is a left side elevational view thereof;

FIG. 6 is a bottom plan view thereof;

FIG. 7 is a rear elevational view thereof; and

FIG. 8 is a sectional view thereof taken along the lines 8—8 of FIG. 7.

FIG. 3

FIG. 4

FIG. 5

FIG. 6

FIG. 7

FIG. 8
